INVENTOR

Hobart L. Needham,

ATTORNEY

UNITED STATES PATENT OFFICE.

HOBART L. NEEDHAM, OF McMINTNVILLE, OREGON.

PERFUME-VENDING MACHINE.

1,271,204.

Specification of Letters Patent.

Patented July 2, 1918.

Application filed December 30, 1915. Serial No. 69,456.

To all whom it may concern:

Be it known that I, HOBART L. NEEDHAM, a citizen of the United States, residing at McMinnville, in the county of Yamhill and

5 State of Oregon, have invented certain new and useful Improvements in Perfume-Vending Machines, of which the following is a specification.

My present invention relates to certain 10 new and useful improvements in perfume vending machines of a type wherein the perfume may be ejected by the operator so as to be applied to the lapel of the coat or at any other suitable point upon the apparel; and 15 as its primary object it contemplates the provision of an improved device of this character but is constructed to be easily operated, cheaply manufactured, and wherein the parts are so arranged whereby they are 20 not liable to get out of order.

A further object of my invention is to provide a device of the type in question that is extremely simple in construction, strong and durable, and highly practical from both the 25 standpoint of the manufacturer and the standpoint of the user; and which, it is believed, may be manufactured at a comparatively low cost.

Various other objects and advantages will 30 become apparent during the continuance of the following description.

These objects are accomplished by such means as are shown in their preferred form in the accompanying drawings, described in 35 the following specification and then more specifically pointed out in the appended claims.

In the accompanying drawings wherein like characters designate like parts throughout the several views:—

Figure 1 is a transverse sectional view taken through the body of the device showing my invention as in its preferred embodiment.

45 Fig. 2 is a fragmentary view illustrating more clearly the coin control mechanism.

In reducing my invention to practice, I first provide a suitable housing, such as designated by the numeral 10 in the drawings, 50 which may be constructed of any suitable or desirable material. The housing is provided at a certain point with a coin receiving slot 11 that is cut away adjacent its lower end as indicated by the numeral 12 so that it 55 may receive an element such as will be hereinafter fully described.

The housing 10 is also provided with a suitable carrying and guiding member 13, which in the present embodiment is in the form of a tubular element (see Fig. 1) to receive an actuating rod 14. A collar 15 is mounted on the carrying rod 14, interiorly of the carrying member 13, and which serves as an abutment to be engaged by one end of the spring element 16. The other end of 60 the spring element 16 normally bears against the internally flanged end 17 of the carrying member so that the actuating rod 14 will be normally held in an inoperative position. Adjacent to the collar 15, the actuating rod 70 is also provided with a projecting lug 18, while at its outer end it carries a handle portion 19. A head portion 20 is mounted at the inner end of the actuating rod 14 and is designed to engage the air bulb of the 75 ejecting mechanism such as will be subsequently pointed out.

The housing 10 is slightly enlarged as at 21 to form a cavity 22 in communication with the coin slot 11, this cavity being of a 80 dimension whereby it may receive an engaging plate or coin-actuating element 23. The engaging plate above mentioned is carried upon a projecting rod 24 that is slidably mounted through one wall of the housing, 85 the latter being provided with a handle portion 25 that merges into the handle portion 19 of the actuating rod. The elements 14 and 20 comprise a pusher, the elements 22 and 24 comprise another pusher or actuator, 90 and the elements 19 and 25 comprise a universal member for operating these pushers. Consequently it will be seen that the actuating rod 14 and the projecting rod 24 may be operated simultaneously. It will also be 95 noted that the plate 23 may be made to seat within the cavity 22 thereby being flush with the front side wall of the coin slot and permitting the free insertion of the coin thereinto such as is obvious.

100 Adjacent to the coin slot 11 is provided a support to which is pivotally secured an engaging arm 27 as shown at 28, the latter being in turn provided with a depending lug or pawl 29 which projects into the carrying member 13 through the slot 30 thereof. In order to provide means to normally retain the engaging arm 27 in an upright position, I provide a suitable resilient element such as indicated by the numeral 31, one 105 end thereof being affixed to the carrying member 13 as at 32, while the other end nor-

normally bears against a lug 33 on the engaging arm.

A perfume container 34 is also mounted in the housing such as shown in Fig. 1, the outlet spout 35 thereof being arranged to open exteriorly of the housing whereby the perfume may be freely ejected therefrom. A stand 36 is mounted within the housing 10 in proximity to the perfume container 10 as at 37, the stand 36 carrying a suitable socket 38 for the reception of the lower end of the air bulb 39. The air bulb may be connected with the outlet 35 of the container by a tube 40 in the usual manner. 15 The head 20 of the actuating rod 14 is adapted to bear against the air bulb 39 of the ejecting apparatus so that by each inward thrust of the actuating rod, the air bulb will be compressed thus ejecting a certain quantity of the perfume from the outlet spout 35, the spring 16 returning the actuating rod to its normal position after the release of pressure on the handle portion 19.

25 In the operation of my invention, it will be seen that under ordinary circumstances the lug 18 of the actuating rod will be spaced from the depending pawl 29 of the engaging arm 37, which will permit slight 30 inward movement of the handle portion 19, as is obvious. The spring 31 retains the engaging arm normally flush with a vertical side of the coin slot (see Fig. 2) whereby the pawl 29 will effectually limit the inward 35 movement of the actuating rod. However, when a coin of the predetermined denomination is deposited in the coin slot such as shown in Fig. 1, immediately upon the inward movement of the actuating rod, the 40 plate 23 acting upon the coin will cause the rocking of the engaging arm 27 so that its pawl 29 will be moved out of the path of movement of the lug 18. As the inward movement of the handle 19 is continued, the 45 coin will be subsequently forced beyond the engaging arm whereupon it will fall into the interior of the housing but when this occurs the lug 18 of the actuating rod will have moved past the pawl 29. As the actuating rod moves farther in this direction, the air bulb 39 of the ejecting apparatus will be compressed so as to force a predetermined quantity of perfume through the outlet spout 35. The spring 16 will also be 50 compressed during this movement so that when pressure is released upon the handle 19, the actuating structure will be automatically returned to its initial position by means of the spring 13.

55 Upon reference to Fig. 1 it will be noted that the engaging arm 27 normally lies flush with the side wall of the coin slot so that it cannot be effectually operated by passing an instrument into the coin slot nor 60 by the use of spurious coins. The coin de-

posited in order to cause the effectual operation of the device, must be of the predetermined denomination in order that the engaging arm 27 will be rocked slightly so as to permit the lug 18 of the actuating rod 70 to move past the pawl 29.

From the foregoing it will be noted that my invention is both efficient in operation, and cheap to manufacture, and that the parts are so arranged whereby they are not 75 liable to get out of order.

In reducing my invention to practice I find that the form referred to herein is the most practical and preferred embodiment and is the most efficient, but realizing that certain conditions will necessarily vary in concurrence with the adoption of my device, I desire to emphasize the fact that various minor changes in the details of construction and in the proportion of parts may be 80 resorted to when required without sacrificing any of the advantages of my invention as defined in the appended claims.

Having thus fully described my invention, what I claim as new and desire to 90 secure by Letters Patent is:—

1. A coin-controlled actuating device comprising in combination a housing having therein a slot for receiving a coin, one of the walls of said slot comprising a movable section, a pusher spaced from said movable section, a member operable for actuating an extraneous object, a stop carried by said movable section of the coin slot wall and adapted to prevent unauthorized operation 95 of said member and means common to said pusher and said member for actuating them when a coin is interposed between said pusher and said movable section, whereby said movable section causes said stop to allow operative movement of said member.

2. A coin-controlled actuating device comprising in combination, a housing having therein a slot for receiving a coin, one of the walls of said slot comprising a pivotally mounted section, a pusher spaced from said pivotally mounted section, a member operable for actuating an extraneous object, a stop carried by said pivotally mounted section of the coin slot wall and adapted to prevent unauthorized operation of said member and means common to said pusher and said member for actuating them when a coin is interposed between said pusher and said pivotally mounted section, whereby said section causes said stop to allow operative movement of said member.

3. A coin-controlled actuating device comprising in combination a housing having therein a slot for receiving a coin and also 125 having a cavity communicating with said slot; one of the walls of said slot comprising a movable section, a pusher spaced from said movable section and normally seated in said cavity so as to be flush with the ad- 130

jacent wall of the cavity, a member for actuating an extraneous object, a stop carried by said movable section and adapted to prevent unauthorized operation of said member, and means common to said pusher and to said member for actuating them when the coin is interposed between said pusher and said movable section, whereby said movable section causes said stop to allow 10 operative movement of said member.

4. A coin-controlled actuating device comprising in combination a housing having therein a slot for receiving a coin and also having a cavity communicating with the slot, a coin-actuating element normally seated in said cavity so as to be flush with the adjacent wall of said slot, a pusher for actuating said coin-actuating element, a coin-actuated element normally forming a por- 15

tion of a wall of said slot and being pivotally mounted and provided with a stop, a member movable to actuate an extraneous object, a stop carried by said member and coöperating with said coin-actuated element for preventing unauthorized actuation of said member, said coin-actuating element and said coin-actuated element being spaced to receive a coin therebetween, and means common to said pusher and said member for actuating them simultaneously when a coin 20 is in position between the coin-actuating element and the coin-actuated element.

In testimony whereof I affix my signature in presence of two witnesses.

HOBART L. NEEDHAM.
